(57) **CLAIM**

The ornamental design for a vibration sensor, as shown and described.

DESCRIPTION

FIG. 1 is a front-right perspective view of the vibration sensor, according to an embodiment of the new design; FIG. 2 is a rear perspective view thereof;

FIG. 3 is a front view thereof;

FIG. 4 is a right side view thereof;

FIG. 5 is a left side view thereof;

FIG. 6 is a top view thereof;

FIG. 7 is a rear view thereof; and,

FIG. 8 is a bottom view thereof.
